UNITED STATES PATENT OFFICE.

HENRY C. SMITH, OF BOSTON, MASSACHUSETTS, ASSIGNOR TO SMITH-WARREN COMPANY OF BOSTON, MASSACHUSETTS, A CORPORATION OF MASSACHUSETTS.

METAL WINDOW-FRAME.

SPECIFICATION forming part of Letters Patent No. 755,585, dated March 22, 1904.

Application filed March 23, 1903. Serial No. 149,132. (No model.)

To all whom it may concern:

Be it known that I, HENRY C. SMITH, a citizen of the United States, residing at Boston, in the county of Suffolk and State of Massachusetts, have invented a new and useful Improvement in Metal Window-Frames, of which the following is a full, clear, and exact description, reference being had to the accompanying drawings, forming a part of this specification, in explaining its nature.

My invention relates to an improvement in metal window-frames.

It consists in the means whereby the separate parts of a frame made of rolled metal may be fitted or joined together without any expensive joining or preliminary fitting of the rolled parts.

The desirability of the rolled-metal frame resides in the fact that by rolling the metal it can be formed in just such configuration and moldings as particularly fit it for making a window-frame. The metal has also when rolled just such a smooth and finished surface as is most desirable. One objectionable feature, though, to making the frame of rolled metal is that in order for the separate head, sill, and jamb portions of the frame to properly join together or be united requires an expensive joining or fitting of the parts and which is attended with more or less waste of the rolled material. This is especially true of the ends of the jambs which unite with the head of the frame. In order to secure a proper sash closure and protection, the head of the frame is ordinarily formed deeply recessed or grooved, so that if the top ends of the jamb portions of the frame were to join with or fit against the head, as they ordinarily do, there would need be a special cutting or finishing of these jamb ends to properly conform to the grooves or recesses formed in the head. The same is true of the lower ends of the jambs, which unite with the sill, but in a lesser degree by reason of the fact that the sill is not ordinarily made so deeply indented or grooved as the head.

By my invention, however, I am enabled to eliminate any pecuniary objection to the use of the

rolled-metal frame structure like as I have referred to, and this by uniting together the 50 separate portions of the frame structure in a way that requires no special finishing of the rolled parts. How this is done, together with other various features pertaining to the adjustability and adaptability of the rolled-metal 55 frame, can best be seen and understood by reference to the drawings, where—

Figure 1 shows the rolled-metal frame structure in vertical section. Figs. 2, 3, and 4 show details in construction thereof, to which mention will hereinafter be made. Fig. 5 shows the rolled-metal jamb as applied to the retention of sliding sashes. Fig. 6 shows the rolled-metal jamb having a face-plate of sheet or rolled metal, to which reference will herein- 65 after be made. Fig. 7 shows the rolled-metal jamb as applied to the retention of a pivoted sash. Fig. 8 shows a modified form of the rolled-metal jamb as applied to the retention of sliding sashes.

Referring to the drawings, A represents the head of the frame, B the sill, and C represents the side portions of the frame or jambs. The head, sill, and jambs are made of separate pieces of rolled metal bolted together. The 75 head and sill have a formation by which they will be best suited to the kind of sash or sashes which they inclose and are also formed with moldings suitable for their architectural fitness and surroundings. The jambs C extend, 80 of course, along either side of the window and between the head and sill and, like the head and sill, are formed in such a manner as will best be suited to the sash or sashes which they serve to inclose; but to this reference will here- 85 inafter be made.

The jambs C are secured to the head and sill, respectively, through the interposition of angle-pieces D, fitting in back of the jambs, to which angle-pieces the ends of the jambs are 90 bolted and which angle-pieces in turn are bolted to the extended ends of the head and sill, respectively. The bolts which secure the ends of the jambs to the angle-pieces are designated c, and d represents the bolts which 95 secure the angle-pieces to the head or sill of

- the frame. There may be as many of these bolts used as may be necessary to obtain a proper retention of the parts. The bolts c , which fasten the jambs to the angle-pieces, may 5 be made with full heads, or these heads may be countersunk, especially if they come in the runways of the jambs in order that there may be no break in their continuity. It is to be noted in connection with these angle-pieces 10 that the jambs C have a longitudinal adjustment relatively to the head and sill. This adjustment is obtained by reason of the slots d , formed in the angle-pieces, and through which slots the bolts d extend, by which the angle-pieces 15 are joined to the head and sill. The slots, of course, permit of some considerable degree of longitudinal play by the angle-pieces, and consequently a longitudinal adjustment of the jambs is obtained, which are 20 secured to the angle-pieces as before described. The feasibility of the adjustable jamb needs no comment.
- By reason of the deeply grooved or recessed formation at the head of the frame and the 25 inclined ledged formation of the sill the ends of the jambs if they were extended to fit or abut against the head and sill would have to be correspondingly formed or cut in order to secure a finished jointure. This joining, however, 30 would be expensive. It would necessitate more or less waste of the rolled material and might prevent altogether the use of the rolled-metal frame. I have obviated this pecuniary difficulty to the use of the rolled-metal frame 35 by squaring the ends of the jambs a short distance from the head and sill, respectively, and then filling the intermediate section left between the ends of the jambs and head and sill with auxiliary portions or pieces having a configuration 40 substantially like that of the head or sill, and so adapted to make jointure therewith in continuation or extension of the jambs proper. I preferably make these auxiliary pieces or portions as an integral part of the 45 angle-pieces D , which unite the separate parts of the frame, as before described. As illustrative of the way in which this is done, I have shown in Figs. 2 and 4 the angle-piece D , having an extension D' , formed especially to fit 50 into a frame-head like as shown in Fig. 1, between which head and the square end of the jamb the said extension is adapted to be interposed as an auxiliary continuation or extension of the jamb, and it is especially to be noted 55 that this portion D' is extended to lie contiguous with the top edge of the jamb, and especially to be flush with its interior facing, whereby the jamb is made to extend, as it were, and conjoin with the head of the frame 60 with a finished jointure. This special formation of the angle-piece just referred to is especially to be distinguished in its formation from the angle-piece shown in Fig. 3, where it performs only the function of holding the 65 two parts of the frame in union, and the jamb

extends up to make its own jointure with the head of the frame. The angle-piece D , which secures the jamb to the sill, may also have an extension D' , adapted to fill the space between the bottom square edge of the jamb and the sill, 70 which extension, of course, would be formed so as to conjoin with its inclined ledged formation.

The angle-pieces D may be cast or forged or made in any other suitable way, especially by 75 which the peculiar formation of their extended section D' may best be obtained. By means of these auxiliary insertions, like as I have described, the rolled-metal portions of the frame require no special finishing in order for them 80 to become united. The rolled portions may even be rolled in lengths and then frame-sections cut therefrom ready to be joined and without waste of material. As before said, the formation of the rolled-metal jambs is 85 such as will best suit them for the peculiar kind of sash or sashes which they inclose. As illustrative of their peculiar adaptability I have shown in Fig. 5 the jamb rolled so as to be adapted for the retention and guidance 90 of vertically-movable sashes. Such retention and guidance may be obtained by means of the rolled exterior and interior flanges $c' c''$ and the sash-dividing flange c^3 .

In Fig. 8 the jamb is shown rolled, so as to 95 provide grooved recesses c^4 , which may receive plates extending from the sashes and which plates are adapted to slide in these recesses for procuring the sliding adjustment of 100 the sashes.

In Fig. 6 I have shown a supplementary plate C' used with the rolled jamb. This plate may be formed of thin rolled or sheet metal, and it may connect with the jamb by any suitable rolled flanged connection, as by being 105 secured to the flanges $c' c''$ and braced by the dividing central flange c^3 . Inasmuch as the metal by its rolling is made to have a smooth surface this supplementary face-plate is unnecessary in so far as the covering up of 110 imperfections or irregularities or roughness in the jamb is concerned; but it is a desirable adjunct to be used with the vertically-movable sashes, especially if weights be used in order to cover up the openings c^5 , (see Fig. 1,) which 115 are cut through each jamb in order that the weights may be inserted through the jambs and placed within their boxes.

In Fig. 7 the rolled jamb is applied to the retention of a pivoted sash, the form of which 120 requires no special mention. It is to be noted, however, that the flanges $c^6 c^7$, to which the pivoted sash structure is secured, can readily be obtained by rolling. In fact, the rolled-metal frame is peculiarly adapted to supply 125 the retention or guidance for any kind of sash or sashes and economically so when it is considered the way in which I obtain the finished jointure of the separate rolled portions constituting the frame. 130

Having thus fully described my invention, I claim and desire to secure by Letters Patent of the United States—

1. A window-frame of rolled metal having an auxiliary piece or portion interposed between the head of the frame and the jamb portions thereof, and designed to make finished jointure or connection between said head and jamb portions, substantially as described.
2. A window-frame of rolled metal having an auxiliary piece or portion interposed between the sill of the frame and the jamb portions thereof, and designed to make finished jointure or connection between said sill and jamb portions, substantially as described.
3. A window-frame the head sill and jamb portions of which are made of rolled metal, and means for uniting said jambs to said head and sill portions of the frame whereby the said jambs may have a longitudinal adjustment relatively thereto.
4. A window-frame the head, sill and jamb portions of which are made of rolled metal, angle-pieces having slots, and means whereby said jamb portions may be adjustably united to said head and sill portions of the frame through the instrumentality of said slotted angle-pieces, substantially as described.
5. A window-frame, the jamb portions of which are made of rolled metal and an auxiliary piece having substantially the configuration of the head of the frame, and adapted to be interposed between it and the top edge of each of its said jamb portions in continuation or extension thereof, substantially as and for the purposes set forth.
6. A window-frame, the jamb portions of which are made of rolled metal and an auxiliary piece having substantially the configuration of the sill of the frame, and adapted to be interposed between it and the bottom edge of each of its jamb portions and in continuation or extension thereof, substantially as and for the purposes set forth.
7. A window-frame, the jamb portions of which are made of rolled metal and auxiliary pieces having substantially the configuration of the head and sill of the frame, respectively,

and adapted to be interposed between said head and sill and the top and bottom edges of each of its jamb portions and in continuation or extension thereof, substantially as and for the purposes set forth.

8. A window-frame, the jamb portions of which are made of rolled metal, angle-pieces for obtaining the jointure of the separate jamb portions of the frame to the head thereof, the said angle-pieces having in extension a configuration substantially like that of the head of the frame, and which extension is adapted to be interposed between it and the top edge of each of its said jamb portions and in extension or continuation thereof, substantially as and for the purposes set forth.

9. A window-frame, the jamb portions of which are made of rolled metal, angle-pieces for obtaining the jointure of the said jamb portions of the frame to the sill thereof, the said angle-pieces having in extension a configuration substantially like that of the sill of the frame, and which extension is adapted to be interposed between said sill and the bottom edge of each of its said jamb portions and in continuation and extension thereof, substantially as and for the purposes set forth.

10. A window-frame, the head, sill and jamb portions of which are made of rolled metal, angle-pieces for obtaining the jointure of the said jamb portions of the frame to the head and sill thereof, respectively, the said angle-pieces having in extension a configuration substantially like that of said head or sill, and adapted to be interposed between said head or sill and the corresponding top or bottom edges of each of its said jambs and in continuation or extension thereof, substantially as and for the purposes set forth.

11. A rolled-metal frame, the separate head, sill or jamb portions of which have in combination therewith and in continuation or extension thereof an auxiliary piece or portion, substantially as and for the purposes set forth.

HENRY C. SMITH.
